United States Patent Office

Des. 191,977
Patented Dec. 26, 1961

191,977

HAT

William C. Flynn, 668 Pickford St., Madison, Wis.

Filed Jan. 18, 1961, Ser. No. 63,607

Term of patent 7 years

(Cl. D3—13)

FIGURE 1 is a side elevational view of a hat, showing my new design, the broken line showing of the wearer being for illustrative purposes only;

I claim:

The ornamental design for a hat, as shown and described.
